United States Patent Office.

ISAAC F. DAVIS, OF ROCKFORD, ILLINOIS.

Letters Patent No. 93,522, dated August 10, 1869.

IMPROVEMENT IN NAIL-EXTRACTOR.

The Schedule referred to in these Letters Patent and making part of the same.

To all whom it may concern:

Be it known that I, ISAAC F. DAVIS, of Rockford, in the county of Winnebago, and State of Illinois, have invented a new and useful Improvement in Nail-Extractors; and I do hereby declare that the following is a full and exact description of the same, reference being had to the accompanying drawings, and to the letters of reference marked thereon.

This invention relates to certain improvements in nail-extracting devices, whereby nails can be drawn when their heads are flush with or slightly below the surface of the wood, to which end certain details of construction are employed, which will be more fully described hereinafter.

In the drawings—

Figure 1 is a plan view of my invention, and

Figure 2, a side elevation of the same.

To enable others skilled in the art to make and use my invention, I will proceed to describe fully its construction and method of operation.

A A' represent the shanks, which are pivoted together at *a*, and provided with the handles B B'.

The shank A' is provided with the head C, which serves as a fulcrum and hammer.

Both shanks A and A' have the triangular projections D D', the points of which project beyond the ends of the shanks and form pincer-jaws.

The jaw D' is attached to the shank A', and projects out from the same sufficiently far for its head to be flush with the jaw D, which is attached to the shank A.

Both jaws are provided with plane surfaces *d d'* on

the inner ends, and may be constructed of steel, welded to the shanks, or the whole may be of the same material.

The operation of my invention is as follows:

The jaws are opened far enough for their points to grasp the head of the nail, and are pressed down into the wood on each side thereof. Should the wood be hard, or the nail driven unusually deep, it is necessary to drive the jaws by striking on the surfaces *d d'*, which are provided for the purpose. When the nail is grasped between the pincers, the handles are borne down, forming a lever whose fulcrum is in the head C. A powerful leverage is thus obtained, and the nail is drawn without bending or otherwise injuring the same, as, when partly drawn, it may be released and another hold taken nearer the wood.

This instrument will be found particularly adapted to merchants and others who have occasion to open boxes, which can be done without affording material injury to the wood or nails.

Having thus fully described my invention, What I claim as new, and desire to secure by Letters Patent, is—

The implement described, consisting of the shanks A A', having the jaws D D' and head C, when arranged to operate as and for the purpose set forth.

This specification signed and witnessed, this 6th day of May, 1869.

ISAAC F. DAVIS.
